UNITED STATES PATENT OFFICE.

FREDERICK W. SPANGLER AND CORTLAND W. DAVIS, OF CHICAGO, ILLINOIS, ASSIGNEES TO THE MANTLE LAMP COMPANY OF AMERICA, OF CHICAGO, ILLINOIS, A CORPORATION OF ILLINOIS.

WICK-CARRIER.

1,285,445.

Specification of Letters Patent. Patented Nov. 19, 1918.

Application filed July 22, 1915. Serial No. 41,341.

To all whom it may concern:

Be it known that we, FREDERICK W. SPANGLER and CORTLAND W. DAVIS, citizens of the United States, residing at Chicago, in the county of Cook and State of Illinois, have invented certain new and useful Improvements in Wick-Carriers; and we do hereby declare the following to be a full, clear, and exact description of the invention, such as will enable others skilled in the art to which it appertains to make and use the same.

One reason for unsuccessful results in the illumination produced by incandescent mantle lamps of the blue flame wick type may be attributed to the improper positioning of the wick within its burner. Realizing the importance of the proper mounting of the wick, it has been proposed to supply a wick carrier with each wick to be dispensed to the customer, wherein the wick has been properly adjusted in its carrier and is ready to be inserted in the burner.

The wick carrier should be so formed that the consumer may readily insert it into a burner so that the new wick will occupy the same relative position for burning as the old one. By a careful and accurate adjustment of the wick and carrier, by skilled workmanship, the consumer may be supplied with a combined wick and carrier which will function properly within the burner and give the maximum efficiency with relatively little labor and trouble on the part of the consumer in the replacement of the wick.

The object of this invention is to supply a wick and carrier for the trade which has been mounted by skilled labor, wherein the consumer is relieved from the trouble and care incident to replacements, thereby increasing the efficiency and utility of a burner and eliminating the undesirable results heretofore experienced by the hap-hazard mounting of the wick within its carrier, by inexperienced persons. The wick being inserted in its carrier by skilled labor may be uniformly positioned in the burner and is presented to the consumer preliminarily charred so that the carrier may be attached to a part of the burner mechanism by the consumer to secure the same results from the new wick as were obtained in the use of the consumed wick.

To insure the proper adjustment of the

wick and carrier within a burner, and to secure efficiency in the operation of the lamp, the wick carrier has been supplied with a rack secured thereto for the purpose of moving the wick carrier within the burner. In this construction, the provision of the rack renders the article expensive, and in the interest of economy it is proposed to supply to the consumer a wick properly mounted within its carrier and having means to be engaged by a detached wick raising rack. In burners wherein the inner tube is supported from the outer tube, the wick carrier may be slotted or bifurcated to span these supports, and these supports may operate to guide the wick in its vertical movement. The supports of the inner tube also serve to limit the vertical movement of the wick by engaging a part of the wick carrier or a part of its elevating mechanism. The elongated slots provided in the wick carrier for its movement with relation to the supports of the inner tube may be closed by means carried by the elevating rack. By so mounting the wick carrier with relation to the tube supports, rotary movement of the wick and carrier is prevented, and also the amount of vertical travel of the wick is limited. The proper mounting of the wick within the carrier will insure its most useful and economical burning position, and the carrier coöperating with the burner parts prevents the use of the wick when the same has passed its useful length.

A practical form of the invention is illustrated in the accompanying drawings, but it is to be understood that the construction therein shown is for the purpose of illustration only, and not as defining the limits of the invention.

In the drawings:—

Figure 1 is a front elevation disclosing a wick mounted in its carrier and a rack secured to a part of the carrier.

Fig. 2 is a detail, sectional view disclosing a part of a burner wherein inner tube supports are positioned in the wick passage.

Fig. 3 is a vertical, sectional view through the structure of Fig. 1 and at right angles thereto.

Fig. 4 is a front elevation of the wick carrier.

Fig. 5 is a rear elevation of a burner rack adapted to coöperate with the wick carrier.

Fig. 6 is a side elevation of the burner rack.

Fig. 7 is a plan view of the rack.

Fig. 8 is a horizontal, sectional view 5 through the wick disclosing the means to secure the wick to the wick carrier.

Referring more particularly to the embodiment of the invention set forth in the accompanying drawings, the wick as indicated at 1, is shown bifurcated at 2 for the lower end of the wick. In using the wick in a burner wherein the inner wick tube such as 3 in Fig. 2 is spaced from the outer wick tube 4 by a vane 5, the wick may straddle 15 the vane in its vertical movement in the burner by means of its bifurcation, indicated at 2. The upper end of the wick is preferably circular in form as indicated at 6 in Fig. 8.

20 The wick carrier may be of any suitable material and may be formed of metal as indicated at 7 and is shown provided with a plurality of perforations 8 which serve to lighten the structure and at the same time 25 prevent conduction of heat to the fuel in the reservoir. The wick carrier 7 may be provided with any suitable means to engage the wick, one form of engaging means being shown as the prongs 9 positioned at the 30 upper and lower edges of the wick carrier.

The wick carrier is preferably provided with an elongated slot 10 which extends from the lower edge 11 of the wick carrier to a point 12 near the upper end of the 35 wick carrier. The walls forming the lower part of the slot 10 are preferably contracted at 13 to thereby form a narrower slot 14 at the lower portion of the wick carrier. The carrier may be provided with a plurality 40 of the slots 10 arranged opposite to each other as shown in Fig. 3 to coöperate with a plurality of vanes 5 carried by the burner. The open end of one of the slots 10 may be closed by means carried by a 45 detachable burner rack indicated at 15.

The lower part of the wick carrier is shown provided with a plurality of lugs 16 which are shown formed by angular or bayonet slots 17 positioned adjacent the contracted end 14 of the slot 10.

50 The lower part of the rack 15 is shown provided with a plate 18, which may be formed with oppositely positioned ears 19 at the upper edge thereof. The plate 18 is 55 preferably offset from the rack 15 as illustrated in Fig. 6 whereby the rack when attached to the wick carrier may be positioned parallel to the wick carrier for contact with suitable elevating mechanism carried by the 60 burner. The plate 18 is shown arcuate in form to conform to the configuration of the wick carrier, and the ears 19 are shown arcuate to engage the curved wick carrier.

In applying the rack to the wick carrier, 65 the lower end of the wick carrier is con-

tracted, whereupon the lugs 16 on opposite sides of the slot 14 may be passed between the ears 19 of the rack plate 18 until the ears register with the notches 20 of the bayonet slot 17, whereupon pressure may be 70 released from the wick carrier to permit the ears to engage the notches 20 and lock the rack to the carrier. The plate 18 will then serve to close the lower end of the slot 10. When the wick carrier and its wick have 75 been properly mounted within the burner, and the vane 5 passed within the slot 10, the end 12 of the slot 10 will serve to limit the downward movement of the wick within the lamp by the engagement of the wick 80 carrier with the upper edge of the vane 5, and the plate 18 will prevent undue elevation of the wick within the lamp by its engagement with the lower edge of the vane 5. This arrangement will serve to preclude the 85 use of a wick beyond its predetermined burning capacity, and the vanes of the burner will serve to guide the wick in its vertical travel within the burner and prevent rotary movement of the carrier with relation to the wick tube.

By the construction herein illustrated and described, the consumer may be supplied with a wick properly mounted within its carrier to be attached to a wick raising rack 95 which may be furnished as a part of the lamp burner, thus reducing the cost of supplying a mounted wick to the consumer as well as reducing the labor on the part of the consumer as compared with rewicking 100 an old burner with a mounted wick.

It is obvious that various changes may be made in the form and proportion of parts, and the right is reserved to make such changes and alterations in the wick carrier 105 and its detachable rack as may fairly fall within the scope of the appended claims.

Having thus described our invention, what we claim is new and desire to secure by Letters Patent is:—

1. In a burner, a wick carrier provided with an open-ended longitudinal slot to permit of contraction and expansion of the slotted end of the carrier, and provided also with a locking slot adjacent the longitudinal 115 slot adapted to be engaged by a wick elevating device which is retained on the carrier by the locking slot due to the contraction and expansion of the slotted end of the carrier.

2. As an article of manufacture, a wick-carrier provided with a plurality of elongated open-ended slots extending longitudinally of the carrier, a plurality of notches in said carrier adjacent the open end of the elongated slot, and means to engage said plurality of notches and substantially close an open end of the elongated slot.

3. As an article of manufacture, a combined wick and wick carrier, the carrier be- 130

ing provided with an elongated open-ended slot extending longitudinally of the carrier, the walls forming said slot being contracted near the lower end of the carrier, and a 5 notched lug formed at the lower end of said carrier to be engaged by means to close said slot, said carrier being provided with means to engage a wick.

4. A wick carrier provided with an open-ended slot, lugs positioned one on each side of said slot and a burner rack having means to detachably engage the lugs.

5. In a burner, a wick carrier provided with an open-ended slot, a plurality of lugs 15 near the open end of the slot, a rack bar having a plate to close said slot, and ears carried by the plate to engage the lugs of the wick carrier to retain the same into engagement with an interposed wick and secure the rack bar to the carrier.

6. In a burner, a wick carrier provided with an open-ended slot, a plurality of lugs near the open end of the slot, a rack bar having an arcuate plate to close said slot, 25 and arcuate ears positioned on the plate to engage the lugs of the wick carrier to retain the same into engagement with an embraced wick and secure the rack bar plate substantially flush with the carrier.

30 7. As an article of manufacture, a wick carrier provided with an open ended slot extending longitudinally of the carrier, and a plurality of rack-engaging notches in said carrier adjacent the open end of the slot.

35 8. As an article of manufacture, a wick carrier provided with an open ended slot extending longitudinally into the carrier, a plurality of rack engaging notches in said carrier adjacent the open end of the slot, 40 and a row of teeth at an end of the carrier

bent into clamping engagement with an interposed wick.

9. As an article of manufacture, a combined wick and wick carrier, the wick carrier being provided with a longitudinal 45 open-ended slot to permit of contraction of the slotted end of the carrier, and means on the wick carrier positioned on each side of the slot to be engaged by a detachable carrier adjusting device which is applied to and 50 maintained on the carrier by the contraction and expansion of the carrier.

10. As an article of manufacture, a combined wick and wick carrier comprising a substantially tubular wick having a bifurcated 55 portion, and a carrier mounted exterior of the wick which is provided with an elongated slot to register with the bifurcated portion of the wick, the wick carrier being provided also with means to be detachably 60 engaged by a burner rack for operating the wick within a burner, which rack when applied to the carrier serves to limit the movement of the carrier in one direction.

11. As an article of manufacture, a combined wick carrier and rack having an extended slot in the body of the wick carrier and a plate on the rack for closing an end of said slot, the length of the slot being sufficient to admit of the raising of the wick 70 when in use until a predetermined portion of the same has been burned away.

In testimony whereof we affix our signatures in presence of two witnesses.
